UNITED STATES PATENT OFFICE.

JAMES L. SIBLEY, OF MARIETTA, GEORGIA.

DESIGN FOR A BADGE.

SPECIFICATION forming part of Design No. 25,657, dated June 23, 1896.

Application filed May 20, 1896. Serial No. 592,366. Term of patent 3½ years.

To all whom it may concern:

Be it known that I, JAMES L. SIBLEY, a citizen of the United States, residing at Marietta, in the county of Cobb and State of Georgia, have made a certain new and useful Design 5 for a Badge; and I do hereby declare the following to be a full, clear, and exact description of the invention, such as will enable others skilled in the art to which it appertains to make and use the same, reference being had to the accompanying drawings, and to letters of reference marked thereon.

In the accompanying drawings, Figure 1 is an edge view of the design; and Fig. 2 is a 15 face view thereof, showing same as it would appear when worn.

In the figures like reference-marks indicate corresponding parts in all the views.

A is a pitchfork, and B are bug-shaped protuberances on the tines thereof, one being on each tine near its point.

C is a pin which should project toward the free end of the handle, and D are spurs which project from the tines on the back side of the badge in a direction opposite the pin C.

Having thus described my design, what I claim as new, and desire to secure by Letters Patent of the United States, is—

The design for a badge substantially as herein set forth.

In testimony whereof I hereunto affix my signature in presence of two witnesses.

JAMES L. SIBLEY.

Witnesses:

A. P. WOOD,
S. M. WOOD.
